UNITED STATES PATENT OFFICE.

WILLIAM H. BOYD, OF HELENA, OKLAHOMA.

RAIL-CONTROLLER.

1,108,688.

Specification of Letters Patent. Patented Aug. 25, 1914.

Application filed September 17, 1913. Serial No. 799,278.

To all whom it may concern:

Be it known that I, WILLIAM H. BOYD, a citizen of the United States, residing at Helena, in the county of Alfalfa and State of Oklahoma, have invented new and useful 5 Improvements in Rail-Controllers, of which the following is a specification.

The present invention relates to means for compensating for the expansion and contraction of railroad rails, the object being to provide a structure whereby the rails will be prevented from buckling and forced out of register when they are expanded and for pulling apart and breaking the joint fastenings when they are contracted, and wherein 15 the gage of the track will be perfectly maintained regardless of the climatic changes to which they are subjected.

With the above and other objects in view, 20 the improvement resides in the construction and arrangement of parts set forth in the following specification and falling within the scope of the appended claim.

In the drawings: Figure 1 is a top plan view of a railway rail provided with my improvement, and showing the position of parts when the rails are expanded by heat, Fig. 2 is a similar view but illustrating the position of parts when the rails are contracted by cold, Fig. 3 is a transverse sectional view on the line *a—a* of Fig. 1, Fig. 4 is a similar view on the line *b—b* of Fig. 1, Fig. 5 is a similar view on the line *c—c* of Fig. 1, Fig. 6 is a similar view on the line *d—d* of Fig. 1, Fig. 7 is a perspective view of one of the compensating rails, and Fig. 8 is a detail view in perspective of one of the brackets.

While it is well known, it is considered 40 appropriate that a brief statement regarding the effect of climatic changes upon railway rails be made. The natural expansion of the metal causes the rails to crowd ahead to the point of least resistance, as at the lap of the 45 rail joint. This expansion naturally crowds the rails at this point, and as a consequence bends the rails and forces the same out of proper engagement, the result of which being the derailment of the rolling stock 50 which passes over the rails. When the rails are contracted by cold the action is reversed. The contraction of the metal causes the rails to draw apart at points of least resistance (as for instance at the lapped joints of the 55 rails). The said contraction frequently pulls the joint fastenings apart or breaks

the securing elements of the said joint fastening, and as a consequence, renders the tracks susceptible to lateral movement, or out of proper engagement, which also frequently results in the derailment of the train which travels upon the tracks. The above effects upon the rails are especially true when the rails are subjected to intense heat or to intense cold, and it may be considered 60 the primary object of the invention to provide simple, cheap and effective means, which may be readily applied at desired points upon any ordinary construction of rail joint and which will effectively and automatically provide compensating means to brought out of proper gage and alinement under all weather conditions.

In the drawings, the main rails are designated by the numerals R—R and R'—R'. 75 The rails R, in the showing of the said drawings have their ends cut angularly, as indicated by the numerals 1. The ends of the said rails have secured thereto angle bars 2, which project a suitable distance from the 80 said ends, and in addition to the angle bars I provide the tie, T which is disposed below the said rail ends with a metallic plate 3, which is secured thereto in any desired or preferred manner, the said plate serving 85 as a rest for the ends of the rails R, and extending a suitable distance beyond the outer edges of the angle bars 2. Removably connected with the extending ends of the plate 3 are brace members 4 which contact with 90 the outer vertical members of the angle bars, and, in the present instance, I have found it desirable to provide the angle bars 2 with heads or crests 5 which abut with the outer faces of the heads of the rails R. The ties 95 T may be sunk a distance below the remaining ties equaling the thickness of the plate 3, and the rails R are secured to the remaining ties through the medium of the usual spikes S.

The rails R' have their ends terminating quite a distance away from the angular ends 1 of the rails R and the said rails R' have their outer faces beveled or inclined toward their ends, as indicated by the numerals 6. 100 These rails R' have secured thereto spaced transversely arranged connecting plates 7, the said plate in the showing of the drawings being connected with the inner faces of the rails, but, of course, the said plates may be connected with the rails R' in any other 105 suitable or desired manner. It will be noted

that one of the plates is disposed adjacent the ends of the rails R', and the second plate disposed a suitable distance from the first mentioned plate, the plates 7 providing 5 means for properly gaging the rails R' and preventing the lateral movement of the said rails toward each other. In addition to the plates 7, the rails to the outer edge of the outer spacing plate are secured to the ties by 10 the spikes S.

My compensating means includes the employment of two rail sections indicated by the numerals 8—8. Each of these rail compensating rail members 8 includes a longitudinal or straight portion 9 which has its end beveled, as at 10, to interlock or co-act with the beveled end 1 of each of the rails R, and the said rail members 8 further provide angular portions 11 which are bent outwardly from their longitudinal straight portions 9 and which engage with the beveled or inclined portions 6 of the rails R'. The angular portions 11 terminate upon the tie to which the rails R' are spiked, and double-headed spikes 12 may be inserted within the said tie to engage with the outer flanges of the rails R' and the inner flanges of the angular portions 11 of the compensating rails 8.

Additional spikes may be employed which engage with the outer flanges of the angular portions 11 of the compensating rails, but the said spikes are not adapted to interfere with the swinging of the compensating rails, 30 in a manner which will presently be described. The ties T upon which the beveled ends 6 of the rails R' rest, and at the junction of the angular and straight portions 9 and 11 of the compensating rails have provided thereon plates 12 and 13 respectively which underlie the rails R' and the compensating rails. These plates extend a suitable distance to the opposite sides of the rails, and each of the plates has its end provided 40 with an angular bracket 14, and the horizontal portion of each of the brackets is preferably provided with a centrally arranged threaded or bolt extension 15 upon which is arranged a nut 16 as well as a coil spring 17, which abuts with the nut and which has its tension regulated by the adjustment of the nut. The springs enter the hollow ends of, what I will term, pressure members 18, the said members abutting with 50 the webs upon the outer faces or sides of the compensating rails 8, and so forcing the angular portions thereof against the angular end 6 of the rails R'. In addition to the members 18, I have found it desirable to 60 provide the longitudinally straight portions of the compensating rails with openings disposed within their webs and which register with similar openings provided in the webs of the angle bars 2, the said aligning openings being adapted to receive 65

a rod 19 which has its opposite end threaded. Arranged upon the opposite ends of the said bar 19 are pressure members in the nature of tubular elements 20, the ends of the tubes through which the rods pass 70 being provided with only reduced openings sufficient to receive the said rods, while the opposite ends of the tubes are open and are adapted to receive springs 22 and 23 which surround the threaded ends of the rod and 75 abut against the inner faces of the said tubes. Nuts 24 and 25 are provided upon the threaded ends of the rod 19 and washers 26 are preferably disposed upon the said rods between the nuts and the springs, the 80 nuts 24 and 25 being employed for forcing the tubular members 20 and 21 against the outer faces of the angle bars 2 to force the said angle bars into proper contact with the outer walls of the straight portions 9 of the 85 compensating rails 8.

It is, of course, to be understood that a suitable space is arranged between the beveled ends 10 of the compensating rails 8 and the beveled ends 1 of the rails R to permit 90 of the expansion of the rails. It will further be noted that the rails R, as well as the rails R' are prevented, through the medium of the spacing plates or bars as well as through the medium of the angle bars from lateral 95 movement in either direction. Therefore, the said plates are only permitted a longitudinal movement. The compensating rails are also permitted a limited longitudinal movement, but a swinging which is normally 100 prevented by the spring pressure members. We will suppose that the rails R and R' are expanded by the heat. The rails R are moved longitudinally until contacted by the angular ends 10 of the compensating rails 8. 105 The rails R' will also move longitudinally toward the ends of the rails R. It is to be understood that the rails R' are at all times held in proper spaced relation with each other, and such longitudinal movement of 110 the rails will cause the compensating rails 8 to be swung outwardly against the tension of their spring pressure members. It will be further noted by reference to the drawings that the longitudinal portion of the compensating rails is comparatively less than the distance between two of the spikes, while the angular portions of said rails are of a far greater length, but each of said compensating rails is not of a sufficient length to permit 115 of the elements expanding or contracting the said rails to any great extent, and so the rails R' will move on the inclined or angular portions 11 of the rails a sufficient distance to compensate for the expansion of 120 the said rails R', and the rails R will contact with the inclined ends 10 of the short portions 9 of the compensating rails 8 and if the expansion is great enough, will force 125 the same rearwardly or toward the rails R', 130

it being understood that the spring pressure members will give sufficient to allow the rails R' to tightly contact with the angular portions 11 of the compensating rails 8 to swing the said compensating rails away from the said rails R' without bringing the ends of the rails R' out of register with the short straight portions 9 of the compensating rails and out of register with the rails R.

10. When the rails R and R' are subjected to contraction, a precise opposite operation occurs. The compensating rails 8, while subject to an outward swinging movement, may be regarded as stationary, and the spring pressure members acting upon the rails as well as upon the fish plates 2 will force the compensating rails tightly against the inclined portion 6 of the rails R' and hold the inner faces of the straightened portions 9 of the said rails in alignment with the rails R.

From the above description, taken in connection with the accompanying drawings, the simplicity of the device as well as the advantages thereof will, it is thought, be perfectly apparent to those skilled in the art to which such inventions appertain without further detailed description.

Having thus described the invention, what I claim is:

30. In a device for the purpose set forth, registering rails having their ends spaced, angle bars engaging the outer faces of two of the

adjacent rails and extending beyond the ends thereof, brace members for the angle bars, a rod passing through the angle bars beyond 35 the rail ends, tubular members adjustably secured to the opposite ends of the rod, springs within the tubes and exerting a tension upon the angle bars, compensating rails for filling the gaps between the registering 40 rails, each of said compensating rails including a straight and an angle portion and the said straight portions of the said compensating rails having their ends arranged in contact with the ends of the aforementioned 45 rails and also in contacting engagement with the angle bars, the second mentioned pair of registering rails having their sides beveled outwardly from their ends and engaged by the angular portions of the compensating 50 rails, brace means for preventing the lateral movement of the compensating rails in an outward direction, and said brace members permitting a longitudinal movement of the said compensating rails to move the same 55 laterally into contact with the ends of the first mentioned registering rails.

In testimony whereof I affix my signature in presence of two witnesses.

WILLIAM H. BOYD.
